UNITED STATES PATENT OFFICE

MICHAEL W. McARDLE, OF CHICAGO, ILLINOIS

SOLE PLATE FOR LAUNDRY IRONS

Application filed February 2, 1927. Serial No. 165,269.

The purpose of this invention is to provide a sole plate for a laundry iron and the like of which the working face shall be formed by sheet metal adapted to afford a flat surface which will take proper polish without requiring to be machined or ground, as is necessary in the case of a cast iron sole plate; and which may be produced more cheaply than the customary cast iron body of the customary flat iron. It consists in the elements and features of construction shown and described as indicated in the claims.

In the drawings:—

Figure 1 is a perspective view of a sheet metal stamping which constitutes the shell and affords the working face of a laundry iron produced in accordance with this invention in one of its forms.

Figure 2 is a perspective view of the completed sole plate of this form.

Figure 3 is a section at the line 3—3 on Figure 2.

Figure 4 is a plan view of a slightly modified form.

Figure 5 is a section at the line 5—5 on Figure 4.

Figure 6 is a section similar to Figure 5 showing the invention in another modified form.

Figure 7 is a section similar to Figures 5 and 6 showing another modification.

Sole plates for laundry irons and the like have heretofore been made of cast iron, which, for the purpose of receiving proper

polishing finish upon the working face and the beveled peripheral edges, is necessarily ground smooth upon said working face and edges, with the result that the corner bounding the working face at the slightly less than 90° meeting angle of the face and beveled edge, is so nearly mechanically perfect as to constitute a cutting edge liable to cut the fabric upon which the iron operates upon encountering a wrinkle or other slight

protrusion as the iron is moved over the goods. This objectionable characteristic can be prevented only by a final finishing process consisting of grinding the corner to slightly blunt it. There is thus required for the process of finishing the customary cast iron sole

plate, three grinding processes, each of which must be conducted with care and skill, and which, therefore, involve a very considerable fraction of the cost of production. Also in the common construction and process of making these sole plates of cast iron, it is necessary to drill and tap holes from the upper side for attaching a handle, and in the case of electric irons, for securing the upper elements of the structure; and since these holes must not extend to the working face, they must be bored only partly through the thickness of the plate, being what are commonly called "blind" holes, which can be tapped with difficulty, extreme care being required to avoid breaking the taps in the process.

The purpose of the present invention is to avoid the necessity of these three grindings, and at the same time furnish the sole plate with a face adapted to receive even higher polish than that of which the cast iron is susceptible even when most carefully ground, and by entirely avoiding the necessity of grinding to escape the liability of producing a cutting edge; and also to avoid the necessity of tapping blind holes in providing for attaching a handle or other super-imposed parts.

These purposes are accomplished by the structure of the several forms hereinafter described. Referring to the form shown in Figures 1, 2 and 3; the sole plate shown is produced in the following manner: First, there is made a sheet metal shell—by suitable means, as by die stamping—seen in Figure 1, which is peripherally flanged, having a flat bottom, A¹, and flange, A², the latter slightly flexed or inclined inwardly, particularly at the upper part as seen at a², the stamping being produced by the well known methods adapted for producing the peripheral flange integrally, and sufficiently rigid to prevent liability to be flexed outwardly for disengaging from the cast iron body with which it is to be filled as hereinafter described. The next step after the formation of this metal shell consists in mounting fixedly within it as by spot-welding to its flat bottom, steel fittings, B, B, of suitable height to extend entirely up through the cast metal body which is

to be formed as hereinafter described in the shell, and to be exposed at their upper ends at or above the surface of the cast metal body. As illustrated, these fittings consist simply of 5 bored and interiorly threaded blocks adapted to have screwed into them bolts for securing super-imposed parts of the iron. The final step in the production of this sole plate shown in Figures 1, 2 and 3 consists in flowing in- 10 to the cavity of the shell, A, molten metal to substantially fill the same, and allowing the same to solidify therein. The laundry iron sole plate produced as above described, has its working face formed by sheet metal 15 most suitable for taking the polish which is desirable for a laundry iron, without any preparatory machining or grinding such as is necessary to prepare a sole plate of cast iron or the like for polishing. The co-efficient of 20 expansion of sheet steel and cast iron being substantially the same, iron flowing in molten condition into the steel shell and completely occupying the same, is rendered substantially inseparable from the shell, inde- 25 pendently of the circumstance that the flange of the shell is slightly inclined inward, so that it overhangs the cast metal, the almost infinitesimal unevenness of the inner surface of the shell constituting means of mechanical en- 30 gagement of the cast metal therewith. But the slightly inward inclination of the flange consists of further means of insuring absolute rigidity of junction of the shell and its cast metal container. It will be recognized, also, 35 that the process of making this sole plate as described is exceedingly economical, because all the grinding and machining is dispensed with except the mere working of boring and attaching the fittings.

40 In the form of this invention shown in Figures 4 and 5, the filler for the outer shell whose plane surface constitutes the working face of the iron, is a cast iron plate, E, which may be referred to as the body of the sole plate. This 45 plate is enclosed in a metal sheath, D, correspondingly to the shell, A, of the form previously described. The sheet metal blank for forming this sheath being applied upon the under side of the plate, E, is folded up as 50 seen at D², about the beveled peripheral edge of the plate, E, and clinched over upon the margin of the upper side of said plate as seen at D³, where it will be seen that the plate, D, is rabbeted for seating the clinching margin, D³. It will be understood that in the 55 process of folding the sheet metal upon the plate, E, for covering the beveled edge, the corner cannot become acute, but is necessarily rounded as is most desirable for the purpose, and that this would be the fact even though the corner of the cast body, E, upon which the sheath is thus folded would be perfectly acute-angled. But the normal angle of the 60 iron casting will itself be slightly blunt, because the casting will not be subjected to

any grinding process, none being required since the working face and edge of the plate are to be formed by the sheath or shell.

Tapped holes *c* for securing the handle to the sole plate are drilled entirely through the cast body member, E, and tapped before the sheath is applied; and there is thus avoided the difficult process of tapping blind holes.

The sole plate thus formed, it will be seen, has the same superior qualities above pointed out with respect to the form shown in Figures 1, 2 and 3, consisting in that the sheet metal of the sheath is of finer texture than can be produced in cast iron, and that the process of production described is much less expensive than the grinding processes which are dispensed with in employing the sheath and the process of construction above described.

In the form of the invention shown in Figure 7, the shell which is a sheet metal stamping is shewn at M, being first formed with its flange substantially erect, as seen in dotted line, *m*¹, and the filler or body member of the sole plate, seen at N, is die cut from a metal plate of suitable thickness, and therefore has its peripheral edges, *n*, substantially perpendicular to its faces; and its horizontal dimensions are slightly less than the corresponding dimensions of the inner surface of the bottom web of the shell, M; and said filler being lodged in the shell, the peripheral flange, *m*¹, is flexed inward to oblique position for contact with the upper corner of the periphery of the filler plate, N, and may then be clinched down upon the upper margin of said plate as seen in Figure 7. In this form the filler plate is bored through and tapped as seen at *n*¹ to afford means for securing the handle and any other super structure of the iron.

In the form shown in Figure 6, the shell, G, is substantially identical in form with the shell, M, shown in Figure 5, and the filler consists of a series of successively super-imposed relatively thin die cut plates, F, F¹, F², F³, corresponding in horizontal contour to the inner surface of the bottom web of the shell, and the lower-most plate F of the series is slightly less in horizontal dimensions than said inner surface of said bottom web, and each successively super-imposed plate of the series is similarly less in horizontal dimensions than the plate next below it; so that the entire pile or group of these plates presents an inclined peripheral edge and each lower plate has a narrow marginal portion exposed beyond the plate next above it, this narrow margin of the next to the top plate in conjunction with said top plate forming what is substantially a rabbet around the upper margin of the pile, considered as a unit. And the flange, G¹, of the shell, G, formed originally erect or at right angle to the web, as seen at dotted line in Figure 6, is flexed inwardly to inclined position in contact with the upper corners of the peripheral edge of

all the plates of the series except the top plate and is clinched over at its upper margin into the rabbet described, formed at the periphery of the top plate and involving the margin of 5 the next lower plate exposed, as described, around said top plate. In this form, the several plates constituting the filler are provided with holes registering with each other when the plates are assembled symmetrically with 10 respect to each other, and the plates are secured together by the hollow rivets J, inserted through the registered holes and clinched down flush upon the outer faces of the top and bottom plates of the series. The 15 hollow rivets being tapped through and through, serve the purpose of the tapped holes, e, of the form shown in Figures 4 and 5, namely, for securing the handle and other super-imposed parts of the iron. It will be 20 observed that by reason of the peripheral edges of the filler plates in the forms shown in Figures 6 and 7, and the dimensions of the plates being less than the corresponding dimensions of the inner surface of the bottom 25 web of the shell, the shell flange, when flexed inward to engage the upper corners of the filler plates, encloses triangular air spaces around the filler plates for the function of slightly insulating the filler plates at their 30 edges from the acute angular and rounded or blunted periphery of the shell which is of advantage in the service performed by the iron, reducing the radiation of heat from the edges of the filler plates to the inclined flange of 35 the shell which forms the beveled edge of the sole plate, and thereby conserving the heat for heating the working face.

I claim:—

1. A composite sole plate for laundry irons comprising a peripherally flanged sheet metal shell and a metal filler for the same, the shell defining a cavity housing the filler, said flange extending inwardly at its upper edge into locking engagement with the filler to 40 permanently secure these elements together.
2. A sole plate for a laundry iron and the like comprising a sheet metal plate forming the working face of the iron and having an upstanding flange extending inwardly at its 45 upper part defining an upwardly opening cavity; a cast iron element fitting said cavity and completely conformed thereto, and metal fittings consisting of metal parts distinct from said sheet metal face plate and from 50 said cast iron element adapted for attaching 55 superimposed parts to said sole plate.
3. A sole plate for laundry iron comprising a body plate having its top surface of less area than the bottom surface thereof, 60 beveled side surfaces connecting the top and bottom surfaces, a sheet metal sheath fixed to said body and covering the bottom and side surfaces and overhanging the top surface thereof, said sheath defining a rounded edge 65 where the bottom and side surfaces intersect

4. A sole plate for a laundry iron comprising a body plate having its top surface of less area than the bottom surface thereof, beveled side surfaces connecting the top and bottom surfaces, a sheet metal sheath fixed 70 to said body and covering the bottom and side surfaces thereof, said sheath defining a rounded edge where the bottom and side surfaces intersect, and an inwardly turned peripheral flange extending completely around the upper edge of the sheath and overhanging the body in locking relation thereto.

In testimony whereof, I have hereunto set my hand at Chicago, Illinois, this 29th day of January, 1927.
